UNITED STATES PATENT OFFICE.

GEORGE E. BARNHART, OF PASADENA, CALIFORNIA.

DRAWING AND ROLLING MACHINE.

Application filed October 5, 1926. Serial No. 139,583.

It is an object of this invention to provide a machine suitable for use in the drawing of tubes or rods; and it is a particular object of my present invention to provide means permitting an automatic reversal of movement of a carriage or "come-along".

It is a further object of my invention to provide means whereby such reversing movement may be effected either manually or automatically.

It is a further object of my invention to provide means favorable to the use of mandrels or other interior forming elements within tubes, during a drawing operation or during a combined drawing and rolling operation.

It is a further object of my invention to provide drawing (or drawing-and-rolling) means favorable to the use of rotatable die elements,—especially rotatable die elements provided with uniform or varying peripheral channels; and embodiments of my invention may comprise means whereby a closing action between die elements is gradually effected during one movement of a rod, tube or the like between said dies, a reverse movement thereof being accompanied by a corresponding opening movement of said dies.

It is a further object of my invention to provide an organization of the general character referred to which is suitable for use either in the drawing of cylindrical rods or tubes (uniform in diameter) or in the production of tapered effects in rods or tubes; and preferred embodiments of my invention may comprise means permitting either manual or automatic closing (and/or opening) of dies, during the advance and/or retraction of stock therebetween.

Other objects of my invention may be best appreciated from the following description of an illustrated embodiment thereof, taken in connection with the appended claims and accompanying drawings, in which—

Fig. 1 may be referred to as a general plan view, with parts broken away.

Fig. 2 is a side elevational view corresponding to Fig. 1, as viewed from the direction of the arrow 2 but with parts eliminated or broken away.

Fig. 3 is a transverse sectional view, on a slightly enlarged scale, taken substantially as indicated by the broken line 3—3 of Fig.

1, parts being broken away and an alternative type of drawing head being shown.

Fig. 4 is a detailed longitudinal section, taken substantially as indicated by the line 4—4 of Fig. 1, but slightly enlarged, parts being broken away.

Fig. 5 is a detailed view, showing an alternative and manually operable mechanism which may be capable of substitution for gears shown in Fig. 1, for controlling the opening and/or closing movement of dies.

Fig. 6 is a diagram comparable with the righthand portion of Fig. 2, but showing an alternative arrangement of gears, the arrangement shown in Fig. 6 being such as to effect a drawing without rolling,—the peripheral movement of rotatable dies being opposite to the advance of the stock therethrough.

Fig. 7 may be referred to as a diagrammatic horizontal section illustrating a rolling operation in which one or more interior formers are used, within tubular stock and in conjunction with a plurality of pairs of rotatable dies, in the elongation of tubes, the forms shown being adapted to produce a substantially cylindrical and considerably elongated tube.

Fig. 8 is a diagram illustrating the effect produced by a first pair of die rollers operating as illustrated in Fig. 7. (See line 8—8 of said figure.)

Fig. 9 is a view comparable with Fig. 8, but taken substantially as indicated by the line 9—9 of Fig. 7.

Fig. 10 is a top plan detail view, showing a type of die head which may contain die rollers of the character illustrated in Fig. 7,—the die heads shown in this figure and in Fig. 1 being immaterial to the broader aspects of my present invention but more particularly described and claimed in my companion application, Serial No. 131,599 filed August 26, 1926, (Case B).

Figs. 11, 12 and 13 are respectively plan views, upon a somewhat enlarged scale, showing alternating types of so-called "come-alongs" or gripping devices suitable for use, under differing conditions, for the gripping of tubular elements (preferably mounted upon mandrels) during drawing or rolling-and-drawing operations.

Fig. 14 is a transverse sectional view

taken substantially as indicated by the line 14—14, Fig. 13, on a slightly enlarged scale.

Fig. 15 is a similar view, taken substantially as indicated by line 15—15, of Fig. 13.

Fig. 16 is a diagrammatic elevational view taken from the general direction of the arrow 65 of Fig. 1,—to show dies of a preferred type, and a gear train for positively 10 rotating the same.

Referring to the details of that specific embodiment of my invention illustrated in Figs. 1, 2, 3 and 4, a main frame 11 is shown as comprising longitudinally extending channel or flanged members 12, 12' and 13, 13',—the latter members being disposed below and spaced apart somewhat more widely than the former. Although details of frame construction may be regarded as comparatively 15 immaterial, I show the mentioned longitudinal members as supported by uprights 14, resting upon floor members 15 and as braced by diagonals 16, 16'; and I show laterally projecting subsidiary frames 17 and 17', 20 (for the support of shafts and additional parts hereinafter mentioned), as comprising diagonals 18 and 18'.

Upon or near one end of a frame of the general character referred to, I may removably support a die head 19, (or 19') preferably of a special construction, comprising rotatable dies, as hereinafter described; and, in order to manipulate a tubular or other stock, drawing the same through the mentioned head, I may employ means such as a so-called come-along 20, movable parallel with and between the mentioned longitudinal frame members by means such as a sprocket chain 21. The chain 21 is shown as 30 extending over sprocket wheels 22 and 23 respectively secured upon shafts 24 and 25,—one of these shafts being rotated by any suitable power means.

For the purpose last referred to, I may, 45 for example, spline upon a sleeve 25', shown as coaxial with the shaft 25 a double-faced jaw clutch member 26, laterally movable, as by means of a lever 27, into engagement with either a corresponding jaw 28 upon a 50 pulley 29 or into engagement with a jaw 30 upon a pulley 31,—both of said pulleys being presumably in continuous rotation (as by belts, not shown) and one of side pulleys (as, by the pulley 29), being secured to the 55 sleeve 25. This sleeve is shown as provided with a gear (32) in a train by which rotation may be imparted to shaft 25. For example, assuming the pulley 31 to be rotated in the direction indicated by the arrow 31', 60 and the pulley 29 to be rotated in the direction indicated by the arrow 29', (and the mentioned pulleys each to be capable of idle rotation, except when their clutch faces are 65 engaged by the corresponding faces of clutch 26) to get a drawing effect, 26 may engage

30, and to get a reversing or stock-returning effect, 26 may engage 28; and, in either case, motion may be transmitted from gear 32 through gears 33 and 34 (on shaft 35) to the gear 36,—also secured on the mentioned 70 shaft 25; and, if desired, the lever 27 may be provided not only with a forwardly extending handle 37 but with additional means, comprising links 38 and 39, permitting manipulation thereof, from a near or remote point or points, by either or both manual and/or automatic means.

To provide for an automatic shifting of the lever 27, or its equivalent, this lever being shown as pivoted at 40, the come-along 20 (alternative forms of come-along being shown in Figs. 11 to 15, as more particularly described hereinafter), comprising jaws (not shown in Figs. 1-4 inclusive) in what I may term the gripping end 41 thereof, may include side members or links 42, 42' and a block 43; and the latter may be provided with a chain-engaging hook H (releasable by sprocket 21, to prevent over-running) and with an upstanding projection or post 44, 80 apertured to receive a tappet-carrying rod 45, which is capable of limited longitudinal movement and may be provided or connected with any suitable means for manipulating the link 39 or its equivalent, to shift the 85 reverse lever 27.

On the rod 45, or its equivalent, I may adjustably secure tappets 46 and 47, suitably spaced apart and alternatively engageable by the post 44,—the effect of engagement of tappet 47, being a longitudinal shift of the rod 45 (shown as extending through guides G, G') in the direction of the arrow 48 and a corresponding translatory movement of a substantially parallel rod or link 49, shown as connected therewith by a clamp member 50 (permitting relative adjustment) and as adapted to transmit movement to link 39 by way of a lever 51, pivoted at 52 on a bracket or brackets 53, 53' and supported by the 105 main frame 11.

In order that the reverse lever 27 shall reliably remain in one or the other of two extreme positions to which it may be shifted by engagement of the post 44 with tappet 115 46 or tappet 47, the lever 51 may be provided with a third arm 54, upon which is shown an apertured member 55 through which extends a rod 56 which is pivoted to a bracket 57, rigidly secured to the frame 11, and is surrounded by a compression spring 58; and, in order to facilitate a manual shifting of the lever 27 by an operative standing in the vicinity of the drawing head 19, or its equivalent, I may connect the mentioned link 38 120 with an arm 59, rigidly secured upon a longitudinally extending shaft 30, having bearings at 61 and 62, the forward end 63 of this shaft being shown as provided with an arm or handle 64.

In the employment of an organization of the general character described for the elongation of metallic tubes, with any desired thinning, toughening and/or tapering effect, 5 I may employ mandrels within said tubes, or I may use internal forming means of the general character best illustrated in Fig. 7. That is to say, although I may insert a separate mandrel within each tube, before advancing same (in the direction of the arrow 65) sufficiently to permit automatic engagement by the come-along 20, or its equivalent, I may alternatively provide, between rotatable dies 66, 66' (constituting a pair or set) 10 15 a bulbous forming element 67,—securing the same against advance, as by attaching the same to or rendering the same integral with a tension member or rod 68,—shown as threaded at 69 for the reception of nuts 20 70 and 71 and as adapted to be dropped within a notch 72 in any suitable fixed member such as a transversely extending vertical plate 73.

All features of my invention, although 25 capable of various modes of use, are suitable to be used with die heads comprising rotatable dies; and, although preferred forms of die head constitute the subject matter of my copending application mentioned, it is an 30 important feature of my present invention that it provides means for engaging and advancing tubular or other stock, optionally returning the same to an original position relatively to rotatable dies disposed in pairs 35 or sets, one pair or set of rotatable dies being disposed immediately in advance of another and in a novel, cooperative relationship thereto,—areas of contact of said pairs or sets being preferably overlapped in an 40 45 advantageous manner, substantially as indicated, with exaggeration, in Figs. 8 and 9.

From an inspection of the figures referred to it will be seen that each set of two opposing dies reaches part way around the article, and that the dies collectively reach all the 50 way around, with some overlapping.

For example, in addition to the mentioned dies 66, 66' (which may be assumed to be disposed in a horizontal plane) I may employ one or more cooperating pairs, such as the rotatable dies 74, 74', shown as disposed 55 in a plane at right angles to the plane of the dies 66, 66'; and I may interpose between the last mentioned pair or set of dies an additional interior bulbous forming element 75,—shown as integrally connected with the mentioned interior forming element 67. As stated in my mentioned copended application, in case substantially circular cross-sectional outlines are desired, the die elements referred to may advantageously provide peripheral grooves whose cross-sectional outline corresponds, in the bottom thereof, to the arc of a circle or circles; and, 60 65 assuming that the cross-sectional outline of the article being drawn is to be changed and the article elongated (with a corresponding effect in the thinning and toughening of its walls) the action of the first-encountered pair of dies (66, 66') may be substantially 70 that indicated in Fig. 8,—lateral regions 76, 76' being given an accurate cylindrical form (either by a drawing or a combined drawing or rolling effect) whereas intermediate areas 77, 77' are momentarily thickened and caused 75 to protrude. The action of the second or subsequently-encountered pair of dies 74 is, however, such as to "iron out" the intermediate areas 77, 77', producing a substantially 80 perfect cross-sectional outline, although presumably leaving very slight lateral clearances, as to 75', favorable to the removal of the tube or work W from an internal forming element M (whether a mandrel or bulbous enlargement of the general character illustrated in Fig. 7). It will be understood that the cross-sectional outline of any mandrel or other interior forming, whether circular or non-circular, must 85 approximately correspond with the cross-sectional outline of the grooves in the dies used therewith.

Although I may use a come-along 20 of any preferred character, in case a cylindrical product is to be produced by the advance 90 and return of tubular stock through pairs or sets of dies of the general character described, I consider it advantageous to employ a come-along of the general character illustrated in Fig. 11,—this come-along comprising, in addition to the side members 42, 42' and the block 43 carrying post 44, a pair of peripherally roughened cams or grip-effecting eccentrics 78, 78' secured by pivot 79, 79' extending through plates 80, 105 80' at the gripping end 41 thereof. In order to adapt this come-along to use both for pushing and pulling a tube or rod, I show the plates 42, 42' as interconnected by an integral transverse web, 81; and I show the 110 eccentrics 78, 78' as provided with arms 82, 82', interconnected by tension spring 83,—to prevent automatic release of said rod or tube, although permitting manual release thereof by a movement of separation of said 115 arms.

For use in rather light work, employing comparatively short mandrels and dispensing with the spring 83, I may, as illustrated in Fig. 12, pivot ovoidal cam elements or 120 eccentrics 78^a, 78'^a, as by means of pins 79^a, 79'^a, to a floating block 80^a, relying upon an engagement of arms 82^a, 82'^a, integral with said cams and extending through slots in side plates 42^a, 42'^a,—his come-along being 125 adapted to effect an automatic release, upon a reversal of the direction of its movement.

The come-along illustrated in Figs. 13, 14 and 15 is specifically constructed for use in heavy work and in taper-drawing,—as by 130

means involving the use of die-closing and opening devices best illustrated in Figs. 1 and 2,—details of die head construction being more particularly described and claimed in my mentioned copending application. As in the mentioned forms of come-along, I may employ a block 43^b carrying a post 44^b; but the side plates 42^b, 42^{b'} are shown as separately pivoted to said block and as pivoted also to grip-effecting members 78^b, 78^{b'}, pivoted respectively at 79^b and at 79^{b'} to a floating block 80^b. This floating block is however shown as provided with a conical aperture 84^b, adapted to receive a set of correspondingly tapered wedge members 85^b,—the latter being shown as four in number, to apply pressure from all sides and as provided with interior circumferential grooves 86^b, adapted to receive springs 87^b, for the automatic expansion thereof, whenever such expansion is permitted by the retraction of arms 88^b, 88^{b'}, comprised in the members 78^b and 78^{b'}. If desired, in order to keep the mentioned wedges in their intended relationships and in order to provide for the automatic retraction of the same at the end of a return movement, (this come-along being suitable for use on thin stock, with or without a mandrel) the ends thereof may project within and carry a loosely fitting ferrule 89^b, adapted to be engaged by any fixed stop (as, by a transversely extending plate or frame member 90, Fig. 1)—each rod or tube being, in this case, inserted through said ferrule, to be gripped, between said wedges, upon the initiation of a drawing movement, and removed upon its return to the initial position.

When dies are to be opened and/or closed during drawing (or drawing and rolling) movements I may utilize (see Figs. 1, 2 and 16) the rotation of any suitable shaft (as, the shaft 24, carrying sprocket wheel 22 over which sprocket chain 21 extends) to effect the purpose referred to. For example, providing the shaft 24 with a gear 91, (as by means comprising a shock avoiding spring S) and interposing an idler 92, I may drive a gear 93 upon a shaft 94 in the direction indicated by arrow 95, employing the rotation of the shaft 94 to impart the closing and opening movement, in any preferred manner, to suitable dies, as by means, comprising additional gears 96 (on shaft 94), 96' (on a parallel shaft 94' carrying a die element 74^{a'}) 97 (also on shaft 94') 97' (on a parallel shaft and integral with a bevel gear 98)—the latter engaging a co-operating bevel gear 98', on a shaft 98^a, carrying a die 66^{a'}.

The shaft 94 is shown as carrying a die 74^a, mating with the die 74^{a'}; and the shaft 98^a of the bevel gear 98' may be provided not only with the die 66^{a'} but with a gear

98^c, intermeshing with a gear 98^d, by which a shaft 98^b, carrying a die 66^a, to mate with the die 66^{a'}, may be correspondingly but oppositely rotated.

Obviously in case of taper drawing, assuming a movement of approach between the bottom of channels in rotatable dies constituting the pair or set to be effected incidentally to the advance of a tube in the direction indicated by the mentioned arrow 75 48, a reverse movement of the sprocket chain may be relied upon correspondingly to open said dies,—as for the purpose of permitting a taper-drawn tube, or the like, to be removed, and a new tube to be inserted, for 80 a repetition of the described operations, subject to automatic or manual control in the general manner described.

The general mode of operation of my invention having been fully indicated in connection with the foregoing description of parts thereof, I call attention to the fact that lubrication of mandrels and/or stock may be effected by any suitable means, as by circulation of a suitable oil through pipes 90 99 and 100 by means such as a small electric motor 101, an oil reservoir being shown at 102 (with which the mentioned plate 73 may be rigidly connected); and, in case a manual adjustment of die pressure is preferred to 95 the described automatic control thereof, it will be obvious that, as suggested in Fig. 5, the described removable gear 95, may be replaced by means such as a lever or rotating handle 95^c, provided with means such as a 100 socket shaft 94^c, adapted to be secured coaxially of the mentioned shaft 94 by means such as a key or set screw 103.

I mention in conclusion that the die head 19 (or 19'), is intended to be provided with 105 means for effecting a movement of approach between the bottoms of channels in its contained dies, for a closing effect (whether or not the channels therein are uniform in depth) and, in the case of the head 19, this approach may be effected by a rotation of the component dies either in the direction in which the stock is advanced, or in an opposite direction; and, accordingly, I may substitute for the gear arrangements illustrated 110 in Figs. 1 and 2 an alternative arrangement of the general character diagrammatically suggested in Fig. 6,—the gear 93' being, in this case, rotated in a direction opposite to the gear 24' by means comprising an 115 internal gear 92', with which an additional gear 92'', engaging gear 93' may be rigidly, connected.

I show the head 19' as provided with 120 adjusting screws A which may be manipulated either manually or by gears (not shown) thereon, said gears being retainable by pins (not shown) extending through the openings O in said screws; and a self-centering 125 effect may be obtained by some provision for

a free transverse play of the respective dies,—the non-intersecting shafts thereof being preferably placed in as close proximity as is consistent with the avoidance of engagement therebetween; but it should be understood both that the principles of my invention are applicable to the production of either circular or non-circular products (whether uniform or non-uniform in cross-section), and that, in case I gear together two or more sets of dies all provided with peripheral channels varying in depth, a first-encountered set of dies must be given an angular advance, relatively to subsequently-encountered dies, such that the opening between the bottoms of channels in the last-mentioned dies may be, at the time of their action upon a given line or area, substantially the same (in the drawing of, for example, a tapered product having various cross-sections) as the opening previously existent between the bottom of channels in the first-encountered dies, at the time when the latter engaged said line or area. Thus, although Figs. 8 and 9 may be read as pertinent to the drawing of a tapered product, they are not, in that case, to be regarded as simultaneous views.

Although I have herein described a single complete organization embodying my invention, suggesting various alternatives as to subordinate parts and alternative modes of operation, it should be understood not only that various features of my invention might be independently employed but also that additional modifications might be readily devised by those skilled in the arts to which this case relates,—without involving the slightest departure from the scope of my invention, as the same is indicated in the above and following claims.

I claim as my invention:

1. In an organization of the general character described: dies; driving means for said moving means, a clutch member controlling the direction of movement of said driving means; means for releasably engaging stock to be subjected to the action of said dies; means for moving said engaging means relatively to said dies; and means for effecting a reversal of said moving means,—said reversing means comprising a longitudinal member which is slidable relatively to said engaging means and is provided with tappets movable by a member connected with said engaging means arranged to move said clutch member into neutral position; and spring tension means for continuing the movement of said longitudinal member after movement thereof by said engaging means.

2. In an organization of the general character described: dies; means for releasably engaging stock to be subjected to the action of said dies; means for moving said engag-

ing means relatively to said dies; and means predetermining a limit of movement of said last mentioned means, said moving means being operatively connected with means for varying the opening between said dies. 70

3. In an organization of the general character described: dies; means for releasably engaging stock to be subjected to the action of said dies; means for moving said engaging means relatively to said dies; and automatic means including a tension member for effecting a reversal of said moving means, said reversing means being subject to independent manual control. 75

4. In an organization of the general character described: dies; means for releasably engaging stock to be subjected to the action of said dies; means for moving said engaging means relatively to said dies; and automatic means including a spring tension member for effecting a reversal of said moving means, said reversing means to be subject to independent manual control from either of a plurality of points. 80

5. In an organization of the general character described: rotatable dies; means for releasably engaging stock to be subjected to the action of said dies; traveling means for moving said engaging means relatively to said dies; driving means for said traveling means; means operated by said driving means for rotating said dies and means predetermining a limit of movement of said traveling means.

6. In an organization of the general character described: dies; gear means for positively rotating the same; means for releasably engaging stock to be subjected to the action of said dies; traveling means for moving said engaging means relatively to said dies; driving means for said traveling means, means operated by said driving means for operating said gear means; and means predetermining a limit of movement of said traveling means,—said dies being disposed in sets, one set in advance of another, and some of said dies being provided with peripheral channels. 100

7. In an organization of the general character described: dies; gear means for positively rotating the same; means for releasably engaging stock to be subjected to the action of said dies; traveling means for moving said engaging means relatively to said dies; driving means for said traveling means, means operated by said driving means for operating said gear means; and means predetermining a limit of movement of said traveling means,—said dies being disposed in sets, one set in advance of another, and some of said dies being provided with peripheral channels whose bottoms are shaped to produce a predetermined cross-sectional outline in stock passed therebetween. 110 120 125

8. In an organization of the general character described: dies; gear means for positively rotating the same; means for releasably engaging stock to be subjected to 5 the action of said dies; means for moving said engaging means relatively to said dies; and means predetermining a limit of movement of said last mentioned means,—said dies being disposed in sets, one set in advance of another, the dies of successive sets being overlapped as to their areas of engagement of said stock.

9. In an organization of the general character described: rotatable dies; means for releasably engaging stock to be subjected to the action of said dies; traveling means for moving said engaging means relatively to said dies; driving means for said traveling means, means operated by said driving 20 means for rotating said dies; and means comprising a tappet-carrying rod, predetermining a limit of movement of said traveling means,—said engaging means being in the form of a so-called come-along comprising 25 side members spaced apart and pivotally connected with a block which is provided with means for engaging said tappet-carrying rod.

10. In an organization of the general character described: rotatable dies; means for releasably engaging stock to be subjected to the action of said dies; traveling means for moving said engaging means relatively to said dies; driving means for said traveling 35 means, means operated by said driving means for rotating said dies; and means, comprising a tappet-carrying rod, predetermining a limit of movement of said traveling means,—said engaging means being in the 40 form of a so-called come-along comprising side members spaced apart and pivotally connected with a block which is provided with means for engaging said tappet-carrying rod, and comprising also pivotally movable members operative for a gripping effect.

11. In an organization of the general character described; rotatable dies; means for releasably engaging stock to be subjected to

the action of said dies; traveling means for moving said engaging means relatively to 50 said dies; driving means for said traveling means, means operated by said driving means for rotating said dies; and means, comprising a tappet-carrying rod, predetermining a limit of movement of said traveling means,—said engaging means being in the form of a so-called come-along comprising 55 side members spaced apart and pivotally connected with a block which is provided with means for engaging said tappet-carrying rod, and comprising also pivotally movable members operative for a gripping effect, 60 said last mentioned members being pivoted to a part which is disposed between said side members.

12. In an organization of a general character described, pairs of dies provided with peripheral ring channels means whereby the opening between the bottoms of said channels may be varied during rotation thereof, 70 traveling means for drawing stock through said dies, driving means for said traveling means; and means operated by said driving means whereby said dies may be rotated oppositely to the direction in which said 75 stock is advanced.

13. In an organization for drawing the tubular stock: a plurality of sets of rotatable dies, said sets being disposed one in advance of another; and means for varying the 80 rotative adjustment of said dies with the movement and in the same direction as the movement of stock therebetween.

14. In a drawing organization: a plurality 85 of sets of rotatable dies disposed one in advance of another, said sets being provided with means for assuring a predetermined relative movement thereof to one another; and means for drawing stock through said dies at a predetermined rate of travel irrespective of the rate of rotation of said dies.

In testimony whereof, I have hereunto set my hand at Los Angeles, California, this 30th day of September, 1926.

GEORGE E. BARNHART.
